TIE RACK

Shirley Brotherton, 54 S. McGregor Ave.,
Mobile, Ala. 36608

Filed July 16, 1969, Ser. No. 18,228

Term of patent 14 years

Int. Cl. D6—01

U.S. Cl. D33—8

FIG. 1 is a perspective view of the front of the tie rack showing my new design;

FIG. 2 is a perspective view showing the rear thereof;

FIG. 3 is a side elevation view thereof;

FIG. 4 is a top plan view thereof;

FIG. 5 is a front elevation view thereof.

The side of the tie rack not shown is substantially the same in appearance as the side shown in FIG. 3.

I claim:

The ornamental design for a tie rack, as shown and described.
